LLP(57) **CLAIM**

The ornamental design for a wall lamp, as shown and described.

DESCRIPTION

1. Wall lamp

1.1 is a front perspective view.

1.2 is a front view.

1.3 is a rear view.

1.4 is a top view.

1.5 is a bottom view.

1.6 is a right side view.

1.7 is a left side view.

The model consists of a wall lamp; the lamp comprises a flexible band to be joined to the wall in an upper point and a lower point; moreover the lamp comprises a light diffuser having a circular shape; the light source is housed into the light diffuser; the light diffuser is put between the circular bend and the wall and rests in its position due to the action of the formed band.
